CLARK ROOT AND BISHOP BENNETT, OF DE RUYTER, NEW YORK.

Letters Patent No. 74,432, dated February 11, 1868.

IMPROVEMENT IN SAWING-MACHINES.

The Schedule referred to in these Letters Patent and making part of the same.

TO ALL WHOM IT MAY CONCERN:

Be it known that we, CLARK ROOT and BISHOP BENNETT, of De Ruyter, in the county of Madison, and State of New York, have invented a new and useful Improvement in Drag-Sawing Machine; and we do hereby declare that the following is a full, clear, and exact description thereof, which will enable those skilled in the art to make and use the same, reference being had to the accompanying drawings, forming part of this specification, in which—

Figure 1 is a side elevation of our invention, and

Figure 2 is a detail view of the same.

Similar letters of reference indicate corresponding parts.

This invention relates to certain new and useful improvements in hand-power drag-sawing machines, of that class which are geared and driven by hand-levers, whereby they are operated with greater facility than heretofore, as hereinafter explained.

In the accompanying drawings, A is the platform, on which the driving-gear and lever are mounted. B is the hand-lever, and C the saw. The hand-lever has three arms, B' B b, and is suspended at its centre by a swinging fulcrum, f. The saw is attached to the balance-wheel K in the ordinary manner, by a pitman, l, and the gear-connections between the working-shaft J and driving-crank shaft H consist in the spur-wheel and pinion I i, as usual. The swinging fulcrum f consists in a crank-shaft, which rests in the standards g, while the wrist f of this crank-shaft acts as a fulcrum for the hand-lever. The arm b of the lever projects downward, and takes hold of the driving-crank shaft H.

By this construction the annoyance of dead-centres, in starting the machine, is avoided. As one end of the lever is off of a half centre when the other is on it, and the machine being operated by two men, and one end of the lever being always off of the centres, the machine is always ready to start without sticking on a centre. When either end, B or B', of the lever, is at the lowest point of its stroke, then that end is on a centre, but the opposite end of the lever being at the same time elevated to its highest point of stroke, it is off of the centre. Either end of the lever is clear of a centre when elevated to its highest point, or is on a centre when depressed to its lowest point, and by these means the opposite ends of the lever relieve each other in passing the dead-centres, and the annoyance arising from this source heretofore is obviated.

Having thus described our invention, what we claim as new, and desire to secure by Letters Patent, is—

The three-armed lever B, swinging fulcrum f, and driving-devices K l I i H, all constructed and arranged as herein described and for the purpose set forth.

The above specification of our invention signed by us, this 11th day of October, 1867.

CLARK ROOT,
BISHOP BENNETT.
